THERMOSTATIC SWITCH

Theodore E. Graves, West Orange, N. J., assignor
to The Wilcolator Company, Elizabeth, N. J., a
corporation of Delaware

Application March 15, 1944, Serial No. 526,601

13 Claims. (Cl. 200—81.4)

1

This invention relates to a snap-acting thermostat which may be used in various types of control apparatus, but which is particularly suited for controlling electrical heating circuits. The new snap-acting mechanism of the present invention includes a novel leaf-spring snap-acting device provided with means for making or breaking electrical circuits and for releasing a push-button switch.

The snap-acting device of this invention may be used for a variety of purposes in the control of electrical or gas heating apparatus. However, the improved snap-acting apparatus will be described and illustrated in connection with the control and operation of "bake" and "broil" heating elements in the oven of an electric range. It is to be understood that the invention is not limited to the illustrated embodiment.

Various types of control apparatus have been provided for the ovens of electric ranges where such ovens include an electric broiling unit and an electric baking unit, the controls being such as to provide a preheating period during which the baking and broiling circuits are connected in parallel for rapidly heating the oven to approximately the desired temperature. Such control apparatus have also been used in connection with selector switches and transfer switches to provide various heating conditions in the oven.

The improved apparatus of the present invention will be described in connection with its use of "bake" and "broil" circuits for preheating the oven, the automatic elimination of the broil circuit at a predetermined temperature, and the automatic subsequent use of the bake circuit to maintain a predetermined temperature.

An important feature of the present invention is the provision of a leaf-spring snap-acting device which has a sensitive snap but in which all parts may move freely without jamming at any temperature within the range of the thermostat and at the same time be effective without the use of "loading" springs. The device includes a leaf-spring having three tongues, the outer two of which are pivoted in aligned knife-edge bearings under compression by placing a tension on the central tongue sufficient to substantially bow the outer tongues. The free end of the central tongue is attached to the long end of a lever pivoted in such a way as to maintain a tension on the tongue and at the same time adapted to be actuated by a bellows responsive to the temperature changes in the oven. A movable block or insulating saddle provided with electrical contacts is attached to the top of the spring assembly and is adapted to

be snapped into or out of contact with corresponding contact points mounted in the apparatus. A snap of the spring will occur when the free end of the lever attached to the middle tongue passes the dead center of the spring or the point where the spring is pivoted. The free end of the central tongue is preferably attached in spaced relation with respect to the actuating lever so that the pivot point of the spring is offset with respect to the pivot point of the lever. This offset arrangement maintains the opposite end of the actuating lever against the bellows, thus providing the loading force usually found necessary in order to secure a sensitive return action of the bellows, as when the temperature of the oven is falling.

Another feature of the present invention is the provision of a novel snap-acting thermostatic control system which includes the snap-acting mechanism described above, associated with a leverage means for locking and releasing a preheat switch. An oven heating system arranged in accordance with this invention may comprise baking and broiling resistance heating elements in the oven with connections between them, a source of electrical supply including a push-button preheat switch for simultaneously operating the "bake" and "broil" elements, a leverage means for locking the push-button switch in closed position and for releasing the push-button in such a way as to give a visible and audible signal at the end of the preheat. The leverage mechanism functions in cooperation with the bellows and the snap-acting mechanism to maintain the preheat conditions and to cut out the "broil" element at a predetermined temperature. Thereafter, the temperature in the oven is maintained by the "bake" element under the control of the snap-acting thermostatic mechanism. The improved leverage means for locking and releasing the push-button switch operates directly with the snap-acting mechanism without altering its sensitiveness. It comprises an adjustable lever pivoted between the push-button switch and the lower movable portion of the snap-acting mechanism.

A further feature of the present invention is the provision of a novel arrangement of a bellows mounted on a movable stem-bearing or axle centered in the stem or temperature setting screw of an oven regulator dial. The bellows is provided with a contraction limiting means and is mounted between the dial and the actuating lever, and there is direct and positive tension on the bellows from the snap-acting spring, thus avoiding the use of loading or bellows springs. Furthermore,

there are no sliding members to be operated by the bellows, and a very sensitive snap-acting movement is obtained with a minimum of moving parts and a maximum of free action.

The thermostat unit of the present invention is sensitive, compact, convenient to adjust, and lends itself to accurate and convenient mass production. Other important features, objects and advantages of the improved apparatus will be described in connection with the accompanying drawings, in which:

Fig. 1 is an enlarged vertical sectional view of the improved snap-acting thermostat control apparatus of the present invention.

Fig. 2 is a vertical sectional view of the apparatus shown in Fig. 1, taken on the line 2-2 of Fig. 1.

Fig. 3 is a vertical sectional view of the apparatus taken on the line 3-3 of Fig. 1.

Fig. 4 is a broken horizontal sectional view of the dial construction shown in Fig. 1, taken on the line 4-4 of Fig. 1.

Fig. 5 is a front view of a portion of the apparatus shown in Fig. 1, taken on the line 5-5 of Fig. 1 with the dial removed.

Fig. 6 is an enlarged broken detailed view showing the structure of the eccentric button shown in Fig. 1.

Fig. 7 is a front view of the improved snap-acting spring removed from the remainder of the apparatus.

Fig. 8 is a front view of the dial and push-button mounting of the improved control apparatus adapted for use in connection with an electric oven.

Figs. 9, 10 and 11 are wiring diagrams of the thermostatic control apparatus illustrating the various combinations of heating circuits which may be employed.

Fig. 12 is a vertical sectional view showing the structural elements of the metal casing of Fig. 1.

Fig. 13 is an elevational view showing the inside of the casing of Fig. 12.

Fig. 14 is a front view of the actuating lever for the snap-acting spring and bellows arrangement comprising a part of the apparatus shown in Fig. 1.

Fig. 15 is a vertical central sectional view of the actuating lever shown in Fig. 14.

Referring to Figs. 1, 2 and 3 of the drawing, most of the elements of the improved apparatus are enclosed in a metal casing 7, a front bellows housing 10 and a rear Bakelite cover 12, the latter being fastened to the metal casing 7 by means of screws 11. A threaded supporting boss 13 is mounted in the front of the bellows housing 10 and carries a similarly threaded dial stem 14 forming a temperature setting screw. The actuating element for the thermostatic control apparatus comprises a bellows 15 mounted as shown in the housing 10 by means of a stem 8 which extends centrally in, and on which the dial stem 14 rotates. The bellows 15 contains the usual liquid charge adapted for use over the particular temperature range to be employed, and is provided with a capillary tube 16 which is wound in a helical coil around the bellows, passed through an opening in the housing 10 and secured to the metal casing 7 by a clamp 17. The capillary tube 16 is connected to a bulb (not shown) which is located in the oven controlled by the apparatus.

The outer end of the dial stem is threaded beyond the stem 8 and provided with a calibration screw 18 which bears directly against the end of the bellows stem 8 and is used for shifting the bel-

lows with respect to the threaded stem 14. The turning of the stem 14 (in making a temperature setting), or of the calibration screw 18 shifts the bellows in the housing 10, and this motion flexes the helical coil of the capillary 16. The coil is arranged to take this movement; in fact it is normally stressed so as to urge the bellows stem 8 outward against the calibration screw 18. A spring 9 is provided around the screw 18 to hold it from turning with respect to the dial stem 14, unless positively operated. The dial assembly mounted on the stem 14 also includes a friction clamp 22 provided with prongs 23 and 24, extending through recesses 25 and 26 (Fig. 4), which bear against the sleeve or boss 13, a dial finger 30 extending from an annular plate 30' inwardly around the housing 10 for the operation of a transfer switch, and a dial control knob 31 bearing the indicia shown in Fig. 8. These elements of the dial are held in place on a flange 19 by means of screws 20 and 21. The dial knob 31 includes a cross-bar 32 having an opening for the operation of the calibration screw 18, and screws 20 and 21. This opening may be covered by a cover plate 33 having end prongs 34.

The improved snap-acting mechanism of the present invention is mounted directly in series with the bellows and comprises a sheet metal spring 46, the cut-out shape of which is shown in Fig. 7. The spring 46 is mounted to the right of the bellows, as shown in Fig. 1, and comprises outer tongues or legs 47 and 48 and a central tongue 49 having an opening 55, which is hooked over a grooved button 50. The button 50 has an off-center or eccentric threaded portion 75 which is adapted to pass through a hole 52 in an actuating and compensating lever 42, and is secured thereto in the desired position by means of a nut 51. The central tongue 49 is used as a tension member and the eccentric button 50 may be rotated to adjust the tension applied to the tongue 49. The snap-acting mechanism is mounted in a bracket member 35 attached to the lower inside portion of the metal casing 7, as clearly shown in Figs. 12 and 13. This bracket 35 includes a pair of supporting arms 36 and 37 provided with aligned V-shaped grooves 38 in which the lower ends of the spring legs 47 and 48 rest. The ends of the legs 47 and 48 are preferably knife-edged to provide a free pivot. The bracket 35 also includes two spaced outwardly and upwardly-extending arms 39 and 40 having retaining notches 41 for holding the lever 42. The lever 42 is a stiff piece of metal and has approximately the shape shown in Figs. 14 and 15. It includes a pair of arms 43 and 44, each provided with knife-edge supports 45 which are pivoted in the notches 41.

Sufficient tension is placed on the central tongue 49 to bow the outer tongues 47 and 48 as shown in Fig. 1. The stress thus created holds the lever 42 and the spring 46 against their respective pivoting points, and provides a force for an over-centered snap action. It will be noted, as shown in Fig. 1, that the legs 47 and 48 are held in a substantially bowed condition or under compression, and that the lifting action of the central tongue 49 forces the knife edges 45 strongly against the pivots 41. The upper end of the lever 42 is short compared to the lower end, and is provided with a recess 58 for receiving the point of a sharpened pin or stud 59 attached to the end of the bellows 15. The snap-acting mechanism is mounted in the bracket 35 so that the central tongue 49 pulls on the button 50 in a line which is always to the right of the pivot bearings 41.

This pull tends to swing the lever 42 in a counter-clockwise direction on the pivot bearings 41 and therefore provides a substantial loading force against the bellows 15 and insures sensitive action of the bellows without the use of separate loading or bellows springs.

A clip 61 is riveted through the free end or body portion 60 of the spring 46, the rivet being applied through a hole 63. The clip extends through a positioning notch 62 and then substantially horizontally into a saddle 65 of electric insulating material, to which it is attached by a cotter pin 64. The saddle arrangement is substantially the same as that of Waddell, Patent No. 2,197,230, and comprises separated elongated sections 67 and 68, each of which carries a pair of vertically arranged movable contacts bridged by a conductor 70. These conductors 70 are secured respectively to the sections of the insulating material 67 and 68 by fastenings 71. Electric current is supplied to the apparatus through wires connected respectively to a pair of contacts 72 by binding posts and the saddle arrangement 65, together with the conductors 70, serve to bridge the contacts 72 with contacts 73 and 74 mounted in the back cover 12 directly below the contacts 72. The movement of the saddle and movable contacts is restricted by spaced adjustable stop screws 84 which are engaged by projections 85 which preferably comprise an integral part of the insulating material of the saddle structure. The stop screws 84 may be operated from the front side of the metal case 7 and locked in place by means of lock nuts 86. The movement of the lower end of the lever 42 or of the tongue or leg 49 to the right between the pivot points of the bowed legs 47 and 48 snaps the saddle mechanism against the contacts 72, and 73 and 74, so as to supply current to the control and heating apparatus, while the movement of the lower end of the lever 42 to the left causes the saddle to snap to the left against the stop screws 84.

The bellows 15 is provided with an internal stop plug 80 which is adapted to engage a rest block 81 upon the contraction of the bellows to a predetermined extent. This stop provides a convenient method for calibrating the apparatus and for preventing the closing of the contacts when the dial is set to "off." The calibration is carried out by charging the bellows 15, capillary 16, and the bulb (not shown) so that the expanding end of the bellows does not move to unseat the stop 80 until an exact temperature such as 150° F. is reached at the bulb. A calibration mark is then placed on the dial for this point instead of for any lower temperature. Since the contraction of the bellows ceases when the bulb is at 150° F. because of the stop 80, the thermostat may then be accurately calibrated by beginning with this point on the dial. There is no movement of the bellows below the temperature of 150° F. and therefore when the dial is turned to "off" the bridging of the contacts 72 with the contacts 73 and 74 will be broken and the contacts will remain open no matter how cold the bulb may become.

The importance of these features will be apparent when it is realized that in many cases it has been necessary to provide some form of mechanical lock to hold the contacts open in the "off" position. Another advantage of this arrangement is that if fluid should be lost from the bulb or bellows, the contacts would still remain open in the "off" position of the dial. The calibration of the thermostat may be completed without removing or shifting the dial 31, by merely

setting the dial to the temperature of the bulb in the oven, and then, while holding the dial at this point, turning the calibration screw 18 to the right or to the left, until the thermostat snaps and opens the circuit.

Since the thermostatic control apparatus of the present invention is illustrated in connection with an oven provided with "bake" and "broil" resistance heating elements, and the temperature control is used primarily in baking, the contact 13 is connected to both the "bake" and "broil" elements, while the contact 14 is connected to a transfer switch normally connected to the "bake" heating element. The "bake" and "broil" heating elements are normally used alternately; therefore, the transfer switch is provided with a connection to the "broil" element. The push-button "preheat" switch is arranged to supply current to the "broil" heating element independently of the transfer switch. A simplified arrangement of the transfer and push-button switches is shown in Figs. 9, 10 and 11, while the structure of the switches is shown in Figs. 1, 2 and 3, in which they are shown as mounted in a casing 100 of insulating material, attached to the lower part of the metal casing 7 by means of front screws 101 and 102, set through lugs 103 and 104, and by side screws 107 and 108. The threaded holes for the screws are shown at 105, 106 and 109 in Figs. 12 and 13. The transfer switch is mounted in a recess 110, back of a front cover 111, and comprises a "broil" contact 115 on the head of a bolt 113, held in place by means of a nut 112. The bolt 113 provides connections to a lug 114 directly above the nut and to a bus bar 116 having a horizontal portion 117 (Fig. 1) and a depending portion 118 to which is secured a contact 120 for the push-button switch. The terminal 14 is connected to the inlet of the transfer switch through a lug 121 (Fig. 2), mounted on a bolt 123, which also secures a bus bar 124 having a depending portion 125 and a contact 126 for the push-button switch. The bolt 123 also mounts a metal collar 127 and a long brass or copper spring conductor 128 having upper and lower contacts 129 and 130 arranged directly over contact 115. A nut 132 holds the bolt assembly in place and keeps the spring 128 in upward tension so that the contact 129 normally engages a contact 131 mounted under a bus bar provided with a binding post 133 from which a wire leads to the "bake" resistance heating element. The spring conductor 128 may be depressed so that the movable contact 130 engages the contact 115 to supply current to the "broil" heating element instead of the "bake" element, by rotating the dial 31 to "broil" so that the dial finger 30 depresses a beveled slide bar 135 which rests on the spring conductor 128. In this position the finger or blade 30 comes in contact with a stop 82 on the housing 10.

The push-button mechanism of the "preheat" switch, is mounted between the spaced contacts 120 and 126, and comprises a cylindrical metal stem 140 having an end portion 140' of slightly reduced diameter and an elongated portion 148 with a threaded end to which is secured a push-button 143 of insulating material. This button is mounted directly below the dial 31 and is normally held in extended position by a main compression spring 145 which is mounted around a reduced section 141 within a cylindrical opening 144. The push-button assembly also includes a sleeve 149 of insulating material mounted against

the larger section of the stem 140, a sleeve 151 of reduced diameter provided with a flange 150, all of insulating material, and a metal contact bar 152 adapted to bridge the contacts 120 and 126, and mounted over the sleeve section 151 against the flange 150. The bar 152 engages a shoulder of the casing 100 and limits the outward movement of the button 143. The contacts 120 and 126, together with the contact bar 152 and other parts of the apparatus, are mounted in a rectangular cavity 148 of the casing 100. A spring 153 is mounted over the sleeve section 151 in a space 147 between the contact bar 152 and the end of the button section 141. This spring keeps the contact bar against the contacts 120 and 126, when the push-button 143 is pushed in.

One of the important features of the present invention is the provision of means for holding the push-button in place to bridge the contacts 120 and 126, and at the same time provide means automatically operable by the snap-acting mechanism or bellows for opening the push-button and switch, and releasing the push-button at the end of the preheat period, in such a manner as to give an audible and visible signal. The novel means for cooperating with the snap-acting mechanism in this way may be referred to as a trigger or releasable latch comprising a friction pawl 155 having the flat construction and shape shown in Figs. 1 and 3. The pawl 155 is pivoted in a slot cut in a horizontal section of a bracket 154. The lower end of the pawl is provided with a slot 156 which extends over an adjusting screw 158, adapted to urge the pawl 155 toward the head of the screw. A spring may be placed on stem 140' instead of on screw 157. The pawl lever 155 extends above its fulcrum point in the bracket 154 and slightly to the right of the button 50. Opposite the button 50 the pawl 155 is provided with an adjustable screw 159 which is provided with a lock nut 160. The button 50 bears against the screw 159 under the conditions shown in Fig. 1, and its movement to the right is limited so that the pin 59 may, under certain conditions, move away from the lever 42. The portion 140' of the push-button stem 140 extends through a hole 162 drilled at right angles to the metal in the lower portion of the pawl 155. The hole is a sufficiently close fit for the stem section 140' so that while the stem may be pushed freely through the hole into a depression 161, if the pawl is rocked counter-clockwise on its pivot, it will on the other hand bite into and pinch the stem upon any slight movement in the opposite direction, thus holding the stem securely at approximately its innermost position. The bridging contact bar 152 will, therefore, be held firmly against the contacts 120 and 126 under tension of the spring 153.

When the pawl lever is rocked or rotated in a counter-clockwise direction on its fulcrum point, it will release the stem of the push-button which immediately snaps to the left, in Fig. 1, breaking the broil circuit, and returning the push-button 143 to its outward position with a visible movement and an audible snap. The "preheat" or push-button mechanism is designed to cooperate effectively with the snap-acting thermostatic mechanism without affecting the sensitiveness of the latter. When the dial 31 is turned from the "off" position to any desired baking temperature position, the threaded stem 14 moves to the left in the threaded member 13, and permits the bel-

lows 15 to move to the left in Fig. 1. At the same time, the lower end of lever 42 moves to the right, the spring 46 snaps to close the current supply contacts, the button 50 contacts the screw 159 to push the pawl lever 155 in a clockwise direction, so that when the push-button 143 is pushed in to initiate a preheating operation, it is held in place by the pawl lever 155. The oven now is operating under preheat conditions with the circuits connected in parallel in the manner shown in Fig. 10.

Now, as the temperature of the oven approaches the desired point, the bellows 15 gradually expands and moves the lower end of the lever 42 to the left. The adjusting screw 159 on the upper end of the pawl lever 155 follows this movement because of the urging of the spring 158 at the opposite end of the pawl lever. By the time the button 50 moves a predetermined distance 20 from the point where the spring 46 snaps and opens the current supply contacts, the pawl lever has rotated to an angle where it suddenly releases the push-button stem 140. When the straight section of lever 155, which includes the hole 162, approaches nearer to an angle of 90° to the stem 140', it begins to lose its grip, as will be apparent from the description and showing. The head of the adjusting screw 157 stops the further movement of the pawl lever 155 so that the screw 159 25 disengages the button 50 as the lower end of lever 42 continues to move to the left, to the snap position and beyond. The lower portion of the snap-acting mechanism, therefore, is free to move back and forth through the snapping position of the thermostat independent of and without interference by pressure from the pawl lever 155. The adjusting screws 157 and 159 at the opposite ends of the pawl lever 155, are accurately adjusted to release the push-button at the proper 30 point, preferably somewhat before the thermostat causes the spring to snap and open the main contacts. The broil element is thus cut out independently of the bake element and preferably at about 25° F. below the temperature setting for the oven. The cutting out of the broil element at this point avoids overshooting the temperature for which the oven is set. The desired adjustment may be secured by moving the screw 159 until the trigger lever 155 releases the push-button at the desired oven temperature below the dial setting temperature. The means for locking and releasing the push-button acts so positively, that a movement of only two or three thousandths of an inch on the end of the pawl lever 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 heating cycle so as to continue the operation with only the "bake" heating element. The improved apparatus is of simple construction, easy to adjust and operate, and does not require the use of loading springs and hand-locking mechanism such as are commonly employed in the art.

Having described the invention in its preferred form, what is claimed as new is:

1. A temperature control apparatus including a main switch, a thermostat responsive to changes in temperature for opening and closing the main switch, a handle for adjusting said thermostat to different temperature settings, a second switch connected into an outlet of said main switch and normally biased to open position, manually operable means for closing said second switch, a latch mechanism for holding said manually operable means in its switch closing position and for thereby holding said second switch in closed position, and means operable by said thermostat in response to a rise in the temperature to a predetermined temperature with respect to the temperature set by said handle for releasing said latch mechanism and thereby permitting said second switch to open at said predetermined temperature.

2. A control apparatus as defined by claim 1, in which the manually operable means includes a stem and the latch mechanism includes a means for gripping said stem.

3. A temperature control apparatus including a main switch, a thermostat responsive to changes in temperature for opening and closing the main switch, a handle for adjusting said thermostat to different temperature settings, a second switch connected into an outlet of said main switch and normally biased to open position, push button means operable for manually closing said second switch, leverage means adapted to engage the push button means for holding said second switch in closed position when the push button is pushed in, said leverage means being arranged in operative relation to said thermostat so that said push button is released by the thermostat in response to a rise in temperature to a predetermined temperature with respect to the temperature set by said handle.

4. A control apparatus as defined by claim 3 in which the push button means includes a stem and the leverage means includes means for gripping the stem.

5. In a temperature control apparatus including a mounting and a rotatable dial thereon, an expansible and contractible bellows responsive to temperature changes set in said mounting with one end firmly engaging said dial, a lever having one end engaging the end of the bellows opposite the dial, said lever being pivoted in the mounting by means of a pivot closely adjacent to the bellows and thereby providing a short lever section engaging the bellows and a relatively long lever section extending beyond the pivot, a snap-acting spring pivoted in the mounting on the opposite side of said lever from said bellows in laterally spaced relation to the pivot of the lever and having a tension member attached to the long end of the lever by a spacing attachment, a control means operable by said snap-acting spring, said dial, said bellows, said lever and said spring being mounted directly in series and arranged so that the tension of the spring maintains the short end of the lever in sensitive firm engagement with the bellows in any operative position of the lever, thereby avoiding the use of a separate loading means for the bellows.

6. In a temperature control apparatus as defined by claim 5, a second control means in the mounting normally biased to inoperative position, a manually operable member for moving said second control means to operative position, a latch for holding said manually operable member in position to retain said second control means in operative position, and means responsive to the expansion of said bellows for releasing said latch.

7. In a temperature control apparatus as defined by claim 5 in which said snap-acting spring includes a pair of spaced compression spring legs upon which the spring is pivoted and a tension leg mounted between said legs and attached to the spacing attachment on the lever.

8. In a temperature control apparatus including a mounting and a rotatable dial thereon, an expansible and contractible bellows responsive to temperature changes set in said mounting with one end firmly engaging said dial, a lever having one end engaging the end of the bellows opposite the dial, said lever being pivoted in the mounting by means of a pivot closely adjacent to the bellows and thereby providing a short lever section engaging the bellows and a relatively long lever section extending beyond the pivot, a snap-acting spring pivoted in the mounting on the opposite side of said lever from said bellows in laterally spaced relation to the pivot of the lever and having a tension member attached to the long end of the lever by a spacing attachment, a control means operable directly by said snap-acting spring, a second control means normally biased to inoperative position, a manual push button means including a stem for moving the second control means to operative position, a pivoted lever having an aperture on one side of its pivot point through which the stem extends, the end portion of the pivoted lever on the other side of the pivot point being provided with an adjustable means in operative engagement with the first mentioned lever.

9. In a device for controlling electric heating circuits including a main switch for connecting and disconnecting a heating circuit with a current source, a thermostat responsive to changes in temperature for opening and closing the main switch and a handle for adjusting said thermostat to different temperature settings, a lever actuated by the thermostat for opening and closing the main switch, a second switch connected into an outlet of the main switch and normally biased to open position, a manual push means including a stem for moving the second switch to closed position, a stem holding means adapted to engage the stem when the push means is pushed in and to retain it in the pushed in position thereby to hold the second switch in closed position, and means actuated by the movement of the lever in response to a temperature rise for releasing the stem holding means to thereby open the second switch.

10. In a device as defined by claim 9 in which said stem holding means includes a pivoted lever having an aperture through which the stem extends and by which it is adapted to be engaged and held by the pivoted lever.

11. In a device as defined by claim 9 in which the stem holding means includes a pivoted lever having an aperture through which the stem extends, one end of the pivoted lever being in operative engagement with the first mentioned lever.

12. In a device as defined by claim 9 in which the stem holding means includes a pivoted lever

having an aperture on one side of its pivot point and through which the stem extends, the pivoted lever on the other side of its pivot point being provided with an adjustment means in operative engagement with the first mentioned lever.

13. In a temperature control apparatus as defined by claim 5 in which said spacing attachment is adjustable and comprises an eccentric device for increasing or for decreasing the tension on said tension member.

THEODORE ELIOT GRAVES.
